UNITED STATES PATENT OFFICE.

MARION L. NICHOLS, OF NEW YORK, N. Y.

HARVESTING-MACHINE.

SPECIFICATION forming part of Letters Patent No. 414,164, dated October 29, 1889.

Application filed February 12, 1889. Serial No. 299,596. (No model.)

To all whom it may concern:

Be it known that I, MARION L. NICHOLS, of New York, county of New York, State of New York, have invented new and useful Improvements in Harvesting-Machines, of which the following is a full and exact description, reference being had to the accompanying drawings, making part of this specification.

My invention relates to that class of machines in which the frame is supported on three or more wheels, the master-wheel being located in rear of the machine, the front supporting-wheel in advance of the cutters, and an end or grain wheel, the grain being carried to the binding devices between the front and rear supporting-wheels.

The invention consists in a novel manner of controlling the movements of the front supporting-wheel and the relation of the main frame relative thereto and to the ground.

It further consists in certain novel features in the construction and arrangement of parts, all as hereinafter described and claimed.

In the accompanying drawings, Figure 1 is a plan or top view of a harvesting-machine, showing the portion of the frame adjacent to the grain-wheel broken away. Fig. 2 is a perspective view of the front supporting-wheel, showing the means for connecting the same with the main frame, and also the tongue and the mechanism or gearing by which an accelerated speed is imparted to the wheel by the tongue, and showing the lifting-post. Fig. 3 is a similar view showing the mechanism or gearing to provide for the necessary vibration of the tongue consequent to the movement of the team without acting on the wheel to turn the same, and Figs. 4 and 5 are detached views of the gearing that is connected to the tongue and the intermediate gearing with which the same engages. Fig. 6 is a plan or top view of the parts shown in Fig. 2. Fig. 7 is a perspective view of a portion of one of the rear frame-bars of the machine, showing the angle-frame connected thereto and one means for connecting the master-wheel frame with the angle-frame. Fig. 8 is an end view of the frame, showing the grain-wheel, its arm, and the means for connecting the said arm to the main frame. Fig. 9 is a plan or top view of the machine, showing the wheels

and the position the front supporting-wheel is caused to assume in turning the machine, and the line or track in which said wheel and the grain-wheel are caused to travel in turning the machine. Fig. 10 is a perspective view, similar to Figs. 2 and 3, of a modification of the devices for operating and controlling the front supporting-wheel in the movements of the tongue. Fig. 11 is a plan or top view of the same, and Fig. 12 is a longitudinal section through the device.

The main frame is made in an oblong rectangular form, having the rear frame-bars A A, front sill or angle-bar A', cross-bars A², longitudinal bar A³, and end frame-bar A⁵. The rear frame-bars A and cross-bars A² are preferably made of metal tubing or gas-pipe, while the front sill is made in the usual angle form, to which the fingers are attached.

The rear frame-bars A A have connected thereto adjacent to the cross-bars A² an angular frame B, having bearings b b b formed therein for the different shafts from which motion is communicated to the various mechanisms for cutting, delivering, and binding the grain. The master-wheel frame D is connected to this frame B through end bolts d, engaging the side bars thereof, and the lugs or ears d', formed with said frame B, and by a central bolt d², engaging a flange d³, depending from the lower face of said frame B, and said master-wheel frame consists, preferably, of the side bars D' D', connected with the central cross-bar to form an open-ended frame, and in the ends of the side bars D' D' are formed or connected the bearings for the axle E of the master-wheel E'. Brace-rods F are connected to the side bars D' D' and to the frame B to strengthen and form a more rigid connection between the frames B and D.

The front sill or angle-bar A' has mounted thereon near the inner end of the cutting apparatus a lifting-post G, hereinafter referred to. A frame or horn H, bent at its inner portion to conform to the shape of the lifting-post, is provided with arms H' H', through which it is secured to a forward extension of the bar A' by means of bolts h. From the frame or horn H, from a point on each side of the lifting-post, the arms H' of the frame H extend outward and upward in

curved form, and have formed on their upper ends journals h' , on which the lifting-levers, hereinafter referred to, are mounted.

To the ends of the levers II is connected 5 a saddle K , to which is connected the front-supporting-wheel holder K' , and which wheel-holder has extending from the upper face thereof a journal or pin K^2 , which extends through the saddle K and has mounted on its 10 upper end a toothed wheel or gear K^3 .

To the rear end of the tongue is rigidly connected a segmental toothed rack K^4 , and said tongue is mounted on a vertical pivot K^5 near the front end of the saddle K , the 15 toothed face of the segmental rack being formed on the arc of a circle of which the pivot-pin K^5 is the center, and the toothed rack is also provided with an elongated curved slot L adjacent to the teeth and formed on a 20 similar arc of a circle, and which slot is engaged by a pin or stud L' , projecting centrally from the saddle K , and which pin or stud serves to limit the swinging movement of the tongue. A second toothed wheel or 25 gear K^6 is mounted on a stud or pin on the saddle and meshes with the rack and with the toothed wheel or gear K^3 , and from which it will be seen that as the tongue is moved to either side of a right line sufficient to turn 30 the machine the rack will communicate motion to the gear K^6 , and through it to the gear K^8 , and consequently cause the supporting-wheel to be turned in its bearings and to be turned at right angles to the master-wheel, 35 and the machine to be swung or turned on the master-wheel as a center, and the said front wheel to track in the arc of a circle of which the master-wheel is the center, the slot and pin before referred to serving to limit the 40 movement of the tongue, and consequently only permitting said gearing to turn said wheel to the proper angle.

In Figs. 3, 4, and 5 the segmental toothed rack is shown as cut away or mutilated, and 45 is provided at this point with a lug or delay-surface engaging a corresponding lug or delay-surface on the gear K^6 , the engaging-faces being curved in the arc of a circle corresponding to the curve of the rack, and by means of 50 which lugs the tongue is permitted to have sufficient side play consequent to the movement imparted thereto by the team, or to permit of the necessary vibration of the tongue without acting on the wheel to turn 55 the same out of line.

In the modification shown in Figs. 10, 11, and 12 the intermediate toothed gear K^6 , for causing the gear on the pivot of the wheel to move in a proper direction, is dispensed with, 60 and in this case an internally-toothed segment K^7 is employed, which fits over or around and engages the teeth of the toothed gear K^3 on the opposite side of its pivot from that shown in the other views, and by which construction it will be seen that the proper movement is imparted to the gear K^8 on the wheel-pivot to permit the gear K^6 , as above stated,

to be dispensed with, and also to bring the device into more compact form. The internally-toothed segment may be provided with 70 a suitable cap or cover K^8 , secured to or cast therewith to cover the gear-teeth formed thereon, and also the toothed wheel or gear K^3 . The cap or cover K^8 is provided with a similar slot L to engage stop-pin L' , as before described. By this manner of connecting the tongue through the gear with the front supporting-wheel holder, as above described, it will be seen that an accelerated speed is imparted to the wheel by the tongue consequent 80 to the radius of the rack or segment being greater than that of the gear, and that as a consequence it will be only necessary to turn the team slightly to properly turn the machine. The rear ends of the levers II are connected 85 to a chain I' , which chain passes up over a roller I^2 , mounted in suitable bearings in the lifting-post, and being connected to a shaft or windlass I^3 , also mounted in bearings in the lifting-post, and which shaft or windlass 90 is revolved to wind the chain thereon by any suitable mechanism, preferably a worm and gear $I^4 I^5$, as shown. The grain-wheel M is mounted on the end of a bell-crank lever or arms M' , connected to the main frame about 95 centrally of the width of the machine from front to rear, and having the arm on which the axle for said wheel is formed or connected to extend back, so that said axle shall be in line or nearly in line with the rear frame-bar of the machine, and the frame is provided with a guideway or track having a slot formed therein in the arc of a circle of which the pivot of the lever is the center in the usual or any preferred way, and from which it will 100 be seen that, while the supporting-point for the frame on the wheel is near the center of the width from front to rear of the machine, said wheel is brought into a proper position relative to the master-wheel to track on a 105 circle around the master-wheel in turning the machine, and consequently the sliding or end movement of said grain-wheel in turning the machine is prevented.

The master-wheel frame has been described 115 as having a fixed relation to the main frame; but it will be readily seen that the front wheel and mechanism for actuating the same may be used in connection with a master-wheel connected to the main frame in a different 120 manner.

Parts of the machine not herein particularly described and those not shown may be constructed in any usual or preferred way.

The matter herein shown and described for 125 controlling the relation of the front supporting-wheel to the frame and the relation of the frame to the ground is not broadly claimed herein, being made the subject of a separate application, filed February 12, 1889, Serial No. 130 299,597.

Having now described my invention, what I claim as new, and desire to secure by Letters Patent, is—

1. In a harvester, the combination of the saddle, the lifting-levers pivoted to the main frame and having pivotal connections with the saddle, lifting devices connected to the 5 levers, a front-supporting-wheel holder having a swivel-connection with the saddle, a gear mounted on the wheel-holder, and a tongue carrying a gear to actuate the gear on the front-supporting-wheel holder, substantially as described, whereby the main frame 10 may be raised and lowered relatively to the front supporting-wheel, while permitting the front supporting-wheel to be turned, as set forth.

15 2. In a harvester, the combination of a swiv-

eling front supporting-wheel, a tongue, gearing actuated by the tongue for controlling the movements of said front supporting-wheel provided with engaging delay-surfaces, substantially as described, whereby the tongue 20 shall have sufficient side play consequent to the movement of the team without acting on the wheel, as set forth.

In testimony whereof I have hereunto set my hand this 9th day of February, A.D. 1889. 25

MARION L. NICHOLS.
